[57] CLAIM

The ornamental design for a food service tray, as shown
and described.

DESCRIPTION

FIG. 1 is a top plan view of a food service tray showing
our new design;

FIG. 2 is a front elevational view thereof, the rear eleva-
tional view being a mirror image thereof;

FIG. 3 is a sectional view thereof taken on line 3—3 of
FIG. 1;

FIG. 4 is a left side elevational view thereof; and

FIG. 5 is a right side elevational view thereof.

The bottom of the design is flat and unornamented.

FIG. 1

FIG. 2

FIG. 3

FIG. 4

FIG. 5
